UNITED STATES PATENT OFFICE

GLENN L. DIMMICK, OF SCOTIA, NEW YORK, ASSIGNOR TO GENERAL ELECTRIC COMPANY, A CORPORATION OF NEW YORK

OSCILLOGRAPH GALVANOMETER

Application filed November 29, 1929. Serial No. 410,622.

My invention relates to apparatus including a galvanometer for photographically recording sound on a moving light sensitive member and particularly to the structure of 5 the galvanometer by means of which the exposing light beam is reflected and caused to vibrate in accordance with sound controlled current variations.

The galvanometer commonly employed 10 heretofore to translate the amplified current vibrations received from the sound pick-up device into vibrations of the exposing light beam is a standard oscillograph galvanometer forming a part of a well known oscillograph in common use for showing wave 15 forms of alternating currents and similar phenomena. This galvanometer has a bifilar construction, namely, has a slender conductor forming a single loop arranged to 20 rotate in the field of a permanent magnet and immersed in oil. Attached to the two sides of the loop is the mirror whose dimensions usually are .017 of an inch wide by .060 of an inch long. It has long been 25 recognized by those skilled in the art of photographically recording sound that these standard oscillograph galvanometers were for various reasons not as completely adapted to the new use to which they were being 30 put as might be desired. For example, difficulty has been encountered in obtaining on the film sufficient light from the very small mirror with which these galvanometers are 35 provided. The galvanometers, moreover, being of a delicate construction are not well adapted for use by operators who are unskilled in the use of such instruments and where they are liable to receive rough handling or other misuse such as might be 40 expected in the case of a portable sound recorder. It is the object of my invention, therefore, to provide a galvanometer of improved construction by which it is particularly adapted for use in the recording of 45 sound and by which the difficulties and disadvantages of those instruments heretofore employed are largely, if not completely, avoided.

My invention will be better understood 50 from the following description taken in con-

nnection with the accompanying drawings, and its scope will be pointed out in the appended claims.

In the drawing, Fig. 1 shows a common 55 form of optical system including the mirror of my improved galvanometer by which a sound record is photographed on a moving film; Fig. 2 is a full size side view of one embodiment of the galvanometer with a portion of the case broken away; Fig. 3 is a 60 cross sectional view looking upward taken on the plane of the lower faces of the pole pieces and drawn to an enlarged scale; and Fig. 4 is an exploded view of the various 65 parts comprising the galvanometer.

Referring now to the drawings, first to 70 Fig. 1 where with the exception of the mirror the parts are shown at a reduced scale, the sensitive film 1 upon which the sound record is to be made passes up around guide roll 2, over the rotatable drum 3, and around the pressure roll 4. Light from the source 6 is concentrated by the condensing lens 7 and lens 8 to a focal point on the 75 mirror 9, a stop 10 being employed to give the desired sharp edge to the light beam directed on the film. From the mirror the light passes on through the cylindrical lens 12 and the spherical lens 13 to the screen 14 having the narrow aperture 15 therein. By means of the microscope objective 16 a 80 reduced image of the aperture is formed on the film and as the mirror is vibrated in accordance with the sound waves illuminating more or less of the aperture 15 a sound record of the variable width type is produced 85 on the film. It will be understood that the sensitive film is protected by a suitable enclosing casing throughout its passage from the supply magazine to the take-up magazine and that a suitable driving means is provided to move the film at a uniform speed at the point at which the record is made. For the sake of simplicity these features have purposely been omitted from the 90 drawings.

The galvanometer comprising my present invention, which I shall term an oscillograph galvanometer inasmuch as it is adapted to follow all of the high frequency 100

oscillations of the sound waves, has the body or frame 20 of non-magnetic material such as aluminum, the central portion of which is shaped to receive the permanent magnet 21 over which is fastened the cover plate 22. Two pole pieces 23 which are slotted so that each has two pole tips are firmly secured by screws to the frame in a position to contact with the respective poles of the magnet. 5 For the purpose of clamping the magnet poles against these pole pieces I have provided two set screws, one of which is shown at 24, in the frame arranged to engage the magnet. 10 Between the arms of the magnet and secured to the frame is the armature and coil supporting member 26 whose lower portion has the transverse slot 27 and the bore 28 and whose upper portion comprises the two 15 uprights 29. These are recessed on opposite sides to receive the disks 30 each enclosing a coil 31 of many turns of insulated wire and occupying the slots in the pole pieces. The iron armature 32 is fixed at its middle 20 portion to one end of the resilient torsion rod 33, made for example of steel, the other end of which is fixed to the cylinder 34 which is adapted to fit into the bore 28. Tightening of the screws 35 by which the 25 member 26 is attached to the frame serves to firmly clamp the member 34. For damping the free oscillation of the armature two pieces of soft rubber 36 are provided, each supported by a plate 37 and held in position 30 by lugs thereon. The rubber pieces each have a slit 38 into which extends a lug 39 on the end of the armature. From the above description it will be seen that the armature has a limited pivotal movement about the 40 axis of the supporting rod 33.

The mirror 9 which is vibrated by the armature is pivotally mounted at one side of and separately from the armature and is connected therewith in such a manner that 45 the angle through which it is vibrated is many times that of the armature. The mirror 9 is shown directly attached to the support 42 which on one side is rounded and on the other side is flat with a shallow longitudinal groove therein which receives the 50 knife edge 43 formed on the upper end of plate 44. The armature is connected to the mirror support 42 by the strips 45 which move freely in openings in the pole pieces 55 and which in the present case are shown having those ends adjacent the mirror united to form one continuous ribbon or strip which is bent at its middle portion over the curved side of the mirror support 42 and has 60 its ends attached to the ends of the armature. As illustrated the lever arm of the armature is approximately ten times that of the mirror support hence the ratio of the angular deflection of the mirror to that of 65 the armature will be approximately ten.

Plate 44 having the knife edge is shown having two pins 47 which engage in recesses in the frame 20 and constitute a pivotal mounting for the plate. Screw 48 passing with ample clearance through the plate 44 serves to retain the plate against accidental displacement which might result in damage to the strips 45 or to the knife 43. By means of the coil spring 49 on screw 50 the strips 45 are maintained taut and adjustment of the tension is effected by turning the screw 50. In a second plate 52 secured to plate 44 is mounted the small spherical lens 8 forming a part of the optical system. The two coils 55 31 are connected together in series with their free terminals connected to the binding posts 53, and operate as a single coil to modify the flux of the magnet in the armature in the well known manner. 80

While I have shown and described the mirror connected to the armature in a manner to produce an angular movement of the mirror approximately ten times that of the armature it is to be understood that this relation is merely illustrative of the principle involved in my invention as the connection may result in various other relations between those members and still produce the advantages which follow from my invention. For maximum mirror deflection per unit 85 torque applied to the armature I have found by calculation that the ratio of transformation of the angular movement of the armature to that of the mirror has a definite relation to the moments of inertia of the armature and mirror. This relation is that the moment of inertia of the armature should equal the product of the moment of inertia of the mirror with its mounting and the square 90 of the ratio of transformation. In other words maximum sensitivity results if the impedances of the armature and the mirror are matched; that is, if the total impedance of all of the moving parts is twice that of the armature alone. While for the largest 100 deflection of the mirror this rule should be followed closely, a relatively large deflection may be obtained when this relation is only approximately true, a strict compliance with the above stated rule being necessary only for a condition of maximum mirror deflection 105 for a given torque applied to the armature. 110

As a result of the construction described above a mirror may be employed having an area very much larger than that of the oscillograph galvanometer heretofore employed, for example, a galvanometer which I have constructed of the size shown in Fig. 2 and having a mirror approximately one-eighth of an inch square has substantially 115 the same sensitivity and frequency characteristic as has been obtained with the previously used galvanometers with very much smaller mirrors. The large mirror makes it possible to obtain not only more light on 120 125 130

the film but an image more free from color and non-uniformity such as results from the use of a small mirror in connection with ordinary lenses. Relatively less stray light 5 also results from the use of a large mirror because of the larger ratio of silvered surface to the broken edge area. Because of the many turns of the coils 31 as compared with the single turn of the aforementioned 10 galvanometers a much greater torque is applied to the armature; however, by reason of the transformation ratio between armature and mirror movements, the actual movement of the armature is microscopic in magnitude. Hence, although the armature as 15 positioned in the field of the magnet may be in unstable equilibrium, its movements are so extremely slight that any distortional effects produced thereby in the coils are 20 negligible.

My invention is not limited to apparatus including mirror vibrating mechanism having a moving iron armature but is applicable also to apparatus in which the armature of the mechanism is in the form of a moving coil, the term armature being employed in the claims to cover either the moving iron or the moving coil type.

I have chosen the particular embodiment 30 described above as illustrative of my invention and it will be apparent that various modifications may be made without departing from the spirit and scope of my invention which modifications I aim to cover by 35 the appended claims.

What I claim as new and desire to secure by Letters Patent of the United States is:

1. An oscillograph galvanometer comprising a magnet, an armature member 40 mounted for movement in the field thereof, an oscillatable member actuated by said armature member, and connecting means between the armature member and oscillatable member arranged to produce a greater movement of the latter than that of the former, the moment of inertia of the armature member being approximately equal to the product of the moment of inertia of the oscillatable member and the square of the 45 ratio of said movements.

2. An oscillograph galvanometer comprising a magnet, an armature mounted to oscillate in the field thereof, an oscillatable member including a mirror actuated by said armature, and a connection between said armature and member arranged to multiply the angular movement of the armature in the member, the product of the moment of inertia of the oscillatable member and the 55 square of the multiplying factor being substantially equal to the moment of inertia of the armature.

3. An oscillograph galvanometer comprising a magnet, an armature mounted to 60 oscillate in the field thereof, an oscillatable

member including a mirror spaced from said armature and an operating connection between said armature and said member, the lever arm at the armature end of said connection being greater than the lever arm at the oscillatable member end thereof and the total impedance of the moving parts being substantially twice that of the armature alone.

4. An oscillograph galvanometer comprising a magnet, an armature mounted to oscillate in the field thereof, an oscillatable member including a mirror, a bearing for said member, pivotal mounting means for said bearing, a plurality of strips connecting said member with the opposite ends of said armature and arranged to produce a multiplied angular movement of the member, adjustable resilient means for moving said bearing on its mounting to tension the connecting strips, and means for preventing accidental displacement of said bearing.

5. An oscillograph galvanometer comprising a permanent magnet having pole pieces, and a winding associated therewith, a bar armature mounted to oscillate between said pole pieces, a bearing plate having a knife edge, an oscillatable member, including a mirror, engaging said knife edge, ribbons connecting said oscillatable member with said armature, and resilient means engaging said bearing plate for adjustably tensioning said ribbons.

6. An oscillograph galvanometer comprising a permanent magnet having pole pieces and a winding associated therewith, an armature bar, a torsion rod support therefor, an adjustable bearing plate having a knife edge, a mirror support engaging said knife edge, a mirror secured to said support, said pole pieces having openings therein, ribbons extending through said openings and engaging at opposite ends the armature bar and the mirror support, the length of the lever arm at the armature end of said ribbons being a multiple of the length of the lever arm at the mirror support end thereof, a spring engaging said bearing plate for tensioning said ribbons and a lens holder attached to said bearing plate.

7. An oscillograph galvanometer comprising a frame, a magnet attached thereto having pole pieces and a winding associated with the pole pieces, an armature bar, a resilient torsion rod fixedly connected at opposite ends respectively with the frame and the armature bar, an adjustable bearing plate, a mirror support having a bearing on said bearing plate, a mirror secured to said support, ribbons connecting the ends of said armature bar with said mirror support and adjusting means engaging the bearing plate for making taut said ribbons and for tensioning said rod.

8. An oscillograph galvanometer comprising

ing a frame, a magnet attached thereto having pole pieces and a winding associated with the pole pieces, an armature bar, a resilient torsion rod fixedly connected at opposite ends respectively with the frame and the armature bar, a bearing plate having a pivotal bearing on said frame, a mirror support having a knife edge bearing on said plate, a mirror secured to said support, said pole pieces having openings therein, ribbons extending through said openings and connecting the ends of said armature bar with said mirror support and a screw for adjusting the bearing plate to tension the ribbons and the resilient torsion rod.

In witness whereof I have hereunto set my hand this 27th day of November, 1929.
